US0D1103747S

(12) **United States Design Patent** (10) **Patent No.:** **US D1,103,747 S**
(45) **Date of Patent:** **** Dec. 2, 2025**

(54) **CABLE RETAINER**

(71) Applicants: **BAXTER INTERNATIONAL INC.**,
Deerfield, IL (US); **BAXTER**
HEALTHCARE SA, Glattpark (CH)

(72) Inventors: **Sriram Rajaraman**, Tamil Nadu (IN);
Srivathsra Rao, Karnataka (IN);
Michael Marshik, Hopkins, MN (US)

(73) Assignees: **Baxter International Inc.**, Deerfield,
IL (US); **Baxter Healthcare SA**,
Glattpark (CH)

(**) Term: **15 Years**

(21) Appl. No.: **29/905,074**

(22) Filed: **Oct. 16, 2023**

(51) LOC (15) Cl. **09-06**

(52) U.S. Cl.

USPC **D8/356**

(57) **CLAIM**

The ornamental design for a cable retainer, as shown and described.

DESCRIPTION

FIG. 1 is a top left front perspective view of a cable retainer in accordance with an embodiment of the claimed design; FIG. 2 is a front side elevation view of the design of FIG. 1;

FIG. 3 is a back side elevation view of the design of FIG. 1;

FIG. 4 is a right side elevation view of the design of FIG. 1;

FIG. 5 is a left side elevation view of the design of FIG. 1;

FIG. 6 is a bottom plan view of the design of FIG. 1;

FIG. 7 is a top plan view of the design of FIG. 1;

FIG. 8 is a top left front perspective view of a cable retainer in accordance with a second embodiment of the claimed design;

FIG. 9 is a front side elevation view of the design of FIG. 8;

FIG. 10 is a back side elevation view of the design of FIG. 8;

FIG. 11 is a right side elevation view of the design of FIG. 8;

FIG. 12 is a left side elevation view of the design of FIG. 8; FIG. 13 is a bottom plan view of the design of FIG. 8; and, FIG. 14 is a top plan view of the design of FIG. 8.

The dash-dash broken lines in the figures represent unclaimed subject matter and form no part of the claimed design.

1 Claim, 14 Drawing Sheets
